(57) **CLAIM**

The ornamental design for a dartboard number ring, as shown and described.

DESCRIPTION

FIG. 1 is a first perspective view of a dartboard number ring shown with a dartboard.

FIG. 2 is a second perspective view of the dartboard number ring.

FIG. 3 is a front elevational view of the dartboard number ring of FIG. 2.

FIG. 4 is a rear elevational view of the dartboard number ring of FIG. 2.

FIG. 5 is a right side elevational plan view of the dartboard number ring of FIG. 2.

FIG. 6 is a top plan view of the dartboard number ring of FIG. 2.

FIG. 7 is a bottom plan view of the dartboard number ring of FIG. 2; and,

FIG. 8 is a left side elevational view of the dartboard number ring of FIG. 2.

The broken lines in FIG. 1 showing the dartboard are for the purpose of illustrating environmental structure and form no part of the claimed design. All other broken lines show portions of the dartboard number ring that form no part of the claimed design.

1 Claim, 8 Drawing Sheets
